UNITED STATES PATENT OFFICE.

MINNIE M. HARRIS, OF SPOKANE, WASHINGTON, ASSIGNOR OF ONE-HALF TO B. K. SINCLAIR, OF DALLAS, TEXAS.

DESIGN FOR AN ADVERTISING DISPLAY-CARD.

41,460.

Specification for Design.

Patented June 13, 1911.

Application filed January 28, 1909. Serial No. 474,894. Term of patent 3½ years.

To all whom it may concern:

Be it known that I, MINNIE M. HARRIS, a citizen of the United States, residing at Spokane, in the county of Spokane and State of Washington, have invented a new, original, and ornamental Design for an Advertising Display-Card, of which the following is a specification, reference being had to the accompanying drawing, forming a part thereof.

The figure is a view of the card showing my new design.

I claim:

The ornamental design for an advertising display card, as shown.

MINNIE M. HARRIS.

Witnesses:

C. A. PLACKETT,
J. W. McCALLA.
